UNITED STATES PATENT OFFICE

MAHLON E. FIRST, OF CLEVELAND, OHIO, ASSIGNOR TO THE C. O. BARTLETT AND SNOW COMPANY, OF CLEVELAND, OHIO, A CORPORATION OF OHIO

ARTICLE HANDLING DEVICE

Application filed January 25, 1929. Serial No. 335,134.

The present invention, as indicated, relates to an article handling device, and more particularly to a pusher mechanism for transferring articles from one to another of a plurality of conveyors. The principal object of the invention is to provide means whereby articles on one of three conveyors will automatically actuate an operating means for a plurality of pushers, one of which will move a given article from the first to the second conveyor, and the other of which will thereafter automatically move the article from the second to the third conveyor. Another object is to provide automatic operating means for a plurality of pushers whereby the pushers will be successively operated. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of the article handling device showing the relation of the three conveyors and the upper pusher to each other; Fig. 2 is a side elevation showing the relation of the two pusher cylinders to each other and showing the details of the lower pusher; Fig. 3 is a plan view of the pusher operating mechanism; Fig. 4 is a side elevation of one of the pusher operating levers; and Fig. 5 is a side elevation of a counterweighted arm and its connection to a valve operating rod.

The present system is devised primarily for the purpose of handling mold flasks in a foundry. Poured flasks on bottom boards are carried from the point at which the metal is poured to the section of the machine shown in Fig. 1 on a cooling conveyor 1 and are then moved onto the flask conveyor 2 and finally onto the walking grate 3. The operators stand on opposite sides of the walking grate 3 and remove the flasks from the molds, returning the flask to the flask conveyor 2 to be

returned to the molding stations. The conveyor 1 may be of any well known type, though it is preferably power driven, and the conveyor 2 is preferably of the gravity rollertype.

Mounted at the side of the cooling conveyor 1, removed from the flask conveyor 2, are two cylinders 4 and 5 receiving pistons to which are attached piston rods 6 and 7 extending from the ends of the cylinders adjacent the conveyor system. Attached to the free end of the piston rod 7 is a car 8 provided with wheels 9 supported on a trackway 10. Said trackway extends beneath the cooling conveyor and the flask conveyor, that portion of the trackway 10a which is beneath the flask conveyor being somewhat elevated above the plane of that portion 10b which is beneath the cooling conveyor. A connecting portion 11 extends at a sharp angle between the two portions 10a and 10b. The car 8 is provided at its forward end with a pair of upwardly extending fingers 12, carrying at their free ends a cross bar 12', said fingers being spaced as shown in Fig. 1.

Flasks are fed from the conveyor 1 onto a table 1', mounted on the framework of which is a plate 13 carrying a pivot pin 14 on which is mounted a lever indicated generally at 16. The lever 16 is made up of a pair of strips 17 spaced from each other by sleeves 18 mounted on the connecting rivets. The end 19 of the lever 16 is provided at its free extremity with a plurality of apertures 21, any one of which may selectively receive a pin 22 upon which is rotatably mounted a wheel or roller 23. The opposite end 20 is similarly provided with a plurality of apertures 21 for selectively receiving a similar pin 22' supporting a similar roller 23'. As is shown in Fig. 1, the plate 1' is formed with a pair of slots 74 and 75 through which the rollers 23 and 23' may be projected. Adjacent its extremity the end 19 of the lever 16 carries a projection 24 to which is pivotally attached, by means of a pin 26, an arm 25, rigidly mounted on a rock shaft 27. Said rock shaft is supported at one end in a plate 28 attached to said framework and adjacent its opposite end in a similar plate 29 similarly mounted. The shaft 27 extends beyond the plate 29

and an arm 30 is rigidly attached to said extending end. The arm 30 carries at its free end a counterweight 31, and intermediate its ends is provided with a pin 30' to which is pivotally attached a link 32. The link 32 is screw-threaded at its free end as at 33 and is provided with a plurality of adjusting nuts 34 adapted to receive and retain between them the eyeleted end of an operating arm 35 rigidly mounted on a valve operating rod 36. The valve 76 may be of the rotary plug type, and is connected to a source of fluid under pressure by a pipe or hose 77. Said valve 76 is so constructed that, when the arm 35 is rocked in a clockwise direction, the valve is positioned to allow fluid flow through a pipe or hose 78 to the cylinder 4 to project the piston 6, and when the arm 35 is rocked to the position shown in Fig. 5, fluid is allowed to flow to the cylinder 4 through another pipe or hose 79 to retract the piston 6.

Mounted adjacent the plate 13 is a similar plate 43 carrying a pin 44 on which is pivotally mounted a lever 46, such lever being made up of parallel strips 47 spaced from each other by sleeves 48 mounted on the connecting rivets. The end 49 of the lever 46 is provided near its extremity with a plurality of apertures 51 adapted selectively to receive a pin 52 mounting a roller 53; and the end 50 of said lever 46 carries adjacent its end a projection similar to the projection 24 on the lever 16 and similarly connected to a rock shaft 57. The end 50 of said lever further carries a pin 52' mounting a roller 53', and it will be seen that the plate 1' is provided with a pair of slots 80 and 81 through which the rollers 53 and 53' may respectively be projected. Said rock shaft 57 is supported in plates 58 and 59 and carries at its outer extremity an arm 60 to which is attached a counterweight 61 and which is connected to a second valve 82 for controlling fluid flow to the cylinder 5 in the manner described in connection with the arm 30 and the valve operating rod 36, said valve 82 being connected to a source of fluid under pressure through a pipe or hose 83. This second valve 82 is so constructed that when the arm 60 is rocked in a clockwise direction, fluid is admitted to the cylinder 5 through a pipe or hose 85 to retract the piston 7, and when the arm is rocked in a counter-clockwise direction, fluid is admitted to the cylinder 5 through a pipe or hose 84 to project the piston 7. A plate 45 is attached to the extreme end 50 of the lever 46 and extends beneath the end 20 of the lever 16.

The operation of my device is as follows: After metal has been poured into a flask F carried upon a bottom board F', the flask is carried by the conveyor 1 toward that portion of the machine which is shown in Fig. 1. As the flask is carried toward the pusher operating mechanism, its bottom board even-

tually strikes the roller 23' on the end 19 of the lever 16, and depresses that end of the lever. Through the arm 25, the shaft 27 is rocked in a counterclockwise direction, as viewed in Fig. 5, and the valve 76 controlling the cylinder 4 is thus positioned, through the connections 30, 32 and 35 to permit flow through the line 79. Fluid is thereupon admitted to the cylinder 4, and the piston rod 6 is withdrawn, thus clearing the plate 1' for passage of the flask thereacross. The bottom board next strikes the roller 53' on the end 50 of the lever 46, attention being called to the fact that the lever 46 is shorter than the lever 16 to provide for such successive operation. Depression of this end of the lever 46 causes rotation in a counterclockwise direction of the rock shaft 57 and consequent operation of the valve 82 controlling the cylinder 5 to permit fluid to flow through the line 84 to project the piston 7.

As the flask continues to move across the plate 1', its bottom board strikes the roller 53 on the end 49 of the lever 46, thus depressing said end 49, and rotating the shaft 57 in a clockwise direction. The valve 82 is thus positioned to permit fluid flow through the line 85 to the cylinder 5 to retract the piston rod 7. Finally the bottom board F' of said flask strikes the roller 23 on the end 19 of the lever 16 and depresses the same, thus rotating the arm 30 in a clockwise direction. The valve 76 is thus positioned to permit fluid flow through the line 78 to project the piston 6. As the piston 6 moves toward the right as viewed in Fig. 2, it carries with it its attached cross bar 86 which engages the bottom board F' to move said board and flask F laterally onto the conveyor 2.

As the next flask moves onto the table 1', the above cycle is repeated. It first depresses the roller 23' to retract the piston rod 6, and then depresses the roller 53' to position the valve 82 to permit fluid flow through the line 84 to project the piston 7. As the piston rod 7 is forced outwardly from the cylinder 5, the car 8 is moved transversely of the conveyors along its trackway. Its first movement causes the wheels 9 to start to rise along the connecting portion 11 of the trackway, thus moving the fingers 12 toward the right as viewed in Fig. 2 and upwardly, just clearing the right hand edge of the plate 1'. The height of the portion 11 of the trackway 10 is just sufficient to lift the cross bar 12' to a position such that it clears the bottom board F' of the first-mentioned flask on the conveyor 2 and engages such flask F. During further movement of the piston rod 7, the front wheels of the car 8 ride along the raised portion 10a of the trackway with the cross bar 12' in engagement with the flask F, and stripping the flask F from its bottom board and moving the same transversely of the conveyor 2 and onto the walking grate 3, while

the rear wheels 9 of the car 8 move along the lower section 10₅ of the trackway. It will thus be seen that I have provided a pusher wherein the engaging elements thereof are raised into position to contact a member on the upper surface of the conveyor while the piston rod is still allowed a straight horizontal push.

As the second flask continues to move along the plate 1', it first strikes the roller 53, thus positioning the valve 82 to permit fluid flow through the line 85 to withdraw the piston 7; and then strikes the roller 23. When the roller 23 is depressed, the valve 76 is positioned to permit fluid flow through the line 78 to project the piston 6 whereby said second flask is moved laterally onto the conveyor 2.

Through the above described operation of the pushers, the flask is thus moved from the conveyor 1 onto the conveyor 2 and thence immediately onto the walking grate 3 leaving the bottom board on the return conveyor 2. The operation of the walking grate tends to loosen the mold and casting from the flask, and the operator stationed beside the walking grate lifts the flask off the walking grate and places it on the return conveyor 2. The sand, of course, is left with the casting on the walking grate and, due to the action of such grate, is knocked away from the casting and falls through the bars of the grate, while the casting is carried by said grate to the next station. The force of gravity causes the empty flask to move down the roller conveyor 2 to the molding stations where it is again utilized.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. An automatic article handling device comprising two conveyors parallel with each other, and a third conveyor at right angles thereto, a pusher adapted to move articles from the first to the second conveyor, a second pusher adapted to move articles from the second to the third conveyor, and independent automatic means each controlled by an article on said first conveyor for operating said pushers.

2. An automatic article handling device comprising two conveyors parallel with each other, and a third conveyor at right angles thereto, a pusher adapted to move articles from the first to the second conveyor, a second pusher adapted to move articles from the second to the third conveyor, and independent automatic means each controlled by an article on said first conveyor for successively operating said pushers.

3. In a conveyor system comprising three conveyors, a pusher for moving articles from the first conveyor to the second, a second pusher for moving articles from the second to the third conveyor, and separate controlling means for each of said pushers, each controlling means comprising a lever adapted to be moved by an article on the first conveyor, the lever for controlling said first pusher projecting beyond both ends of the lever for actuating said second pusher.

4. A pusher actuating mechanism comprising, in combination, two valves to control fluid supply to pusher-actuating cylinders, a handle for operating each valve, two rock shafts, a counterweighted arm on each rock shaft, a link connecting each valve handle with its respective arm, two levers, one of said levers being wholly positioned between the planes normal to the other lever and defined by the ends thereof, and connections between said rock shafts and said respective levers.

5. In an article handling device, the combination with a plurality of conveyors, of a pusher comprising a power cylinder, and a piston rod extending beyond said cylinder, a trackway extending beneath two of said conveyors and having an elevated portion, and a car on said trackway connected to said piston rod.

6. In an article handling device, the combination with a first conveyor and a second parallel conveyor slightly spaced therefrom of a pusher for moving articles from said second conveyor comprising a cylinder mounted on the side of said first conveyor removed from said second conveyor, a piston rod extending from said cylinder, a trackway extending from a point adjacent said cylinder beneath said first conveyor and, at a higher level, beneath said second conveyor, and a car on said trackway and connected to said piston rod, said car having an extension adapted to engage an article on said second conveyor.

7. In an article handling device, the combination with a pair of parallel conveyors, at least one of which is of the gravity roller type, of a pusher for moving articles from said roller conveyor comprising a cylinder separated from said roller conveyor by said other conveyor, a piston rod extending from said cylinder, a trackway extending from a point adjacent said cylinder beneath both said conveyors, that portion of said trackway beneath said roller conveyor being at a higher level than the remainder thereof, and a car on said trackway and connected to said piston rod, said car having an extension adapted to engage an article on said roller conveyor.

8. In an article handling device, the combination with a pair of parallel conveyors, at least one of which is of the gravity roller type, of a pusher for moving articles from

said roller conveyor comprising a cylinder separated from said roller conveyor by said other conveyor, a piston rod extending from said cylinder, a trackway extending from a point adjacent said cylinder beneath both said conveyors, that portion of said trackway beneath said roller conveyor being at a higher level than the remainder thereof, and a car on said trackway and connected to said piston rod, said car being provided at its forward end with a pair of upwardly extending fingers adapted to be projected between the rollers of said roller conveyor and carrying a cross-bar adapted to engage an article on said roller conveyor.

9. In an article handling device, the combination with a pair of parallel conveyors, at least one of which is of the gravity roller type, of a pusher for moving articles from said roller conveyor comprising a cylinder separated from said roller conveyor by said other conveyor, a piston rod extending from said cylinder, a trackway extending from a point adjacent said cylinder beneath both said conveyors, that portion of said trackway beneath said roller conveyor being at a higher level than the remainder thereof, and a car on said trackway and connected to said piston rod, said car being provided at its forward end with a pair of upwardly extending fingers adapted to be projected between the rollers of said roller conveyor and carrying a cross-bar adapted to engage an article on said roller conveyor, and a pusher for moving articles from said other conveyor to said roller conveyor, comprising a cylinder mounted above said first-mentioned cylinder, and a piston rod extending from said second cylinder and adapted to engage an article on said other conveyor.

10. In an article handling device, the combination with a pair of parallel conveyors, at least one of which is of the gravity roller type, of a pusher for moving articles from said roller conveyor comprising a cylinder separated from said roller conveyor by said other conveyor, a piston rod extending from said cylinder, a trackway extending from a point adjacent said cylinder beneath both said conveyors, that portion of said trackway beneath said roller conveyor being at a higher level than the remainder thereof, and a car on said trackway and connected to said piston rod, said car being provided at its forward end with a pair of upwardly extending fingers adapted to be projected between the rollers of said roller conveyor and carrying an element adapted to engage an article on said roller conveyor, a pusher for moving articles from said other conveyor to said roller conveyor, comprising a cylinder mounted above said first-mentioned cylinder, a piston rod extending from said second cylinder and adapted to engage an article on said other conveyor, and

means adapted to be engaged by an article on said other conveyor for actuating said pushers successively.

Signed by me, this 23rd day of January, 1929.
